UNITED STATES PATENT OFFICE.

EDWARD J. WHELAN, OF WASHINGTON, DISTRICT OF COLUMBIA.

PLAYING-CARDS.

1,064,268.

Specification of Letters Patent. Patented June 10, 1913.

Application filed April 23, 1912. Serial No. 692,603.

To all whom it may concern:

Be it known that I, EDWARD J. WHELAN, a citizen of the United States, residing at Washington, in the District of Columbia, have invented new and useful Improvements in Playing-Cards, of which the following is a specification.

The invention relates to a game, and more particularly to the class of game cards for 10 scoring in the ordinary national base ball game.

The primary object of the invention is the provision of a game in which a series of cards are employed having certain indicia thereon whereby on the playing of the cards the various scores ordinarily incident in the national game of base ball may be had in a given number of innings.

Another object of the invention is the provision of a game in which one or more persons may accomplish, by playing of cards having particular indicia thereon, results incident to the national game of base ball, thus assuring amusement to the players, as 25 well as pleasure causing each player to retain interest throughout the entire game with a view of accomplishing a scoring on the opponent.

A further object of the invention is the provision of a game which affords even 30 chances to all players, that is to say to the opponent in each and all of the innings, thereby avoiding undue advantage of one player over another, the game being beneficial in educating the players in understanding the national game of base ball 35 without requiring skill or excessive labor on the part of the players, yet enabling them to manifest interest and fascination therein.

With these and other objects in view, the 40 invention consists in the employment of a set of cards having indicia thereon with the arrangement thereof as hereinafter set forth, illustrated in the accompanying drawings, and pointed out in the claims hereunto appended.

In the drawings there is shown a series 45 of cards used in the game which will be referred to by reference characters herein-after.

Referring to the drawings, by numerals, 50 10 designates generally each card of a pack of playing cards, the same being of any desirable shape and size, but preferably of the ordinary well-known size and shape and is constructed from any suitable material, for instance, card-board, the pack being composed of fifty cards bearing certain indicia designating the playing of the offensive and defensive players of two teams, which are incident to the well-known game of American national base ball, the cards being designated in a manner as will be hereinafter described.

The game may be played by one or more 65 persons, and is governed by the rules of the American national game. The cards of the pack are shuffled in the ordinary well-known manner, and each card is dealt out of the pack from top down scoring the result of 70 each card until three outs have resulted. The person dealing the cards is designated the representative of the defensive team, while the person to whom the cards are being dealt is designated representative of the 75 offensive team. After the person representing the offensive team has received cards indicative of three outs, he is entitled to the score made during the continued dealing of the cards by the player representing the 80 defensive side, and thereafter such score is listed and the pack of cards are passed to the person representing the offensive side whereupon they are shuffled and dealt to the person representing the defensive team until 85 such player has received cards indicative of three outs, and in this manner through the continued playing of the cards by the respective players, the total score for opponent players is accomplished, it being understood that at least nine innings shall be 90 played before the finish of the game for totalizing the scores made by opponent teams, and such opponent having the larger number of runs wins the game. 95

The cards 10 of the pack are designated from each other by indicia or otherwise designations thereon, as follows: The cards of the pack comprises a series of twelve cards having printed or otherwise indicated 100 thereon the words "Fly out" as at 11, and this series is subdivided, namely, four cards bearing numbers 1, 3, 4, and 5; two cards bearing number 6, three cards each bearing number 7, one card bearing number 8, two 105 cards each bearing number 9. The second series of ten cards, 12, each have printed or otherwise indicated thereon the words "Ground out". This series, 12, of cards is subdivided, namely, one card bearing numbers 1—3, one card bearing numbers 3—3, and two cards bearing numbers 4—3, two 110 cards bearing numbers 5—3, four cards bearing numbers 6—3. The third series, 13, of seven cards has printed or otherwise indicated thereon the words "Base hit", and this series is subdivided, namely, one card bearing the words "Infield", two cards bearing the words "Left" two cards bearing the words "Center", two cards bearing the words "Right". The fourth series, 14, of three cards has printed or otherwise indicated thereon the words "Foul out", and this series is subdivided, namely, one card bearing number 2, one card bearing number 3, and one card bearing number 5. The fifth series 15, of cards, five in number, has printed or otherwise indicated thereon the words "Strike-out". The sixth series 16, of four cards has printed or otherwise indicated thereon the words "Sacrifice hit" and also the words "(See rules)". The seventh series 17, of two cards each bears by printing or otherwise indicating thereon, the words "Stolen base". The eighth series 18, of two cards each bearing by printing or otherwise indicating thereon the word "Walk". The remaining five cards, 19, 20, 21, 22 and 23 of the pack, bear by printing or otherwise indicating thereon, "Two base hit", "Three base hit", "Home run", "Error, (see rules)", and "Hit by pitcher", respectively.

The play of the cards should be governed by the rules, as follows:—

1st. In dealing the card bearing the words "Stolen base", by the defensive player to the offensive player, and the latter has failed to receive a card from the pack indicating a runner on a base, the said "stolen base" card fails to count for the player of the offensive team, but should the latter have received cards indicative of men on successive bases, the said "stolen base" card dealt affords him the credit of the advance of the men on successive bases, that is to say what is known as a "double steal". Now, should the player of the offensive have the credit of one man on first, and one man on third base prior to the dealing of the "stolen base" card, then on dealing the said card it credits the player by advancing one man from first to second base, but does not credit the advance of the man holding third base.

2nd. When any one or more of the "sacrifice hit" cards are dealt by the player of the defensive to the player of the offensive, and it happens that the latter player has the credit of no men on bases, the said "sacrifice hit" card scores as an "out", and gives to the player of the defensive a credit to one member of the team an "out" and to the other member an "assist" when summarizing the general average. Should the player of the offensive have a credit of a man on first base prior to the dealing of the "Sacrifice hit" card and on the dealing of the latter, he is credited with the advance of the man from first to second base, and in addition thereto an "out". Likewise, should the player on the offensive have the credit in the score of a man on third base, first and second, first and third, second and third, or first, second and third bases, when dealt the "sacrifice hit" card, he is credited with the advance of each man a single base, and in addition thereto an "out". Now, should it happen that the player of the offensive is credited to his score 2 "outs" and a "sacrifice hit" card has been dealt to him, the score to the offensive team stands credited with three "outs", thus reversing the position of the players of the game, so that the defensive will now pass the pack of cards to the offensive to be dealt to the defensive for the scoring thereof.

3rd. Should a player of the offensive have no "outs" credited to his score, and on the dealing of a "base hit" card to such player, his score is credited with the advance of a man to a base with the exception in the following instances: Should the player of the offensive be credited with a man on second base, the "base hit" card entitled "Center" credits the score of the offensive by scoring the man on second base to a single run, and should the score be credited with a man on first and the "base hit" card entitled "Right" should be dealt, this credits the advance of the man on first to third base. In dealing the cards entitled "Two base hit", the player of the offensive has his score credited with the advances of men only two bases in any case. Now, should the player of the offensive be credited on the score with a man on third base only and he is dealt a "fly out" card, to the "center fielder" is scored to his credit with a run by the advance of the man on third to home.

4th. When the player of the offensive has been dealt the "error" card, and his score will be credited to the opponent making last "out", and should his score have no "outs" recorded, the first batter of the offensive receives credit therefor. It is to be understood that all other plays are left to the judgment of the player or players, and are valued strictly in accordance with the Rules of the American national game of base ball.

The members of the respective opponent teams are numbered as follows: Pitcher, number 1, catcher, number 2, first base man, number 3, second base man, number 4, third base man, number 5, short-stop, number 6, left fielder, number 7, center fielder, number 8, right fielder, number 9, so that in the dealing of the cards 10 of the pack, having numbers thereon corresponding to the numbers of the teams, it will enable both the player of the offensive and defensive to give credit by way of "outs", "assists", "errors", and the like to the respective members of the teams, and in this manner a complete scoring may be had in accordance with the rules regulating the American national game of base ball.

- 5 In dealing the cards to the players, the same are turned face up upon a table or the like in successive order, and the designations or indicia thereon indicate the scoring of the game to be credited to the opponent 10 player throughout the consecutive number of deals aggregating by counting each deal nine innings, whence the scores are totalized to ascertain the winning player.

From the foregoing description, taken in 15 connection with the accompanying drawings, it is thought that the construction and purpose of the game will be thoroughly understood, and therefore, a more extended explanation has been omitted.

20 What is claimed is:—

1. A pack of playing cards consisting of a single deck, having the individual cards provided with matter designating the character of play and having certain cards provided, in addition to the indicating matter, with other designating matter to give credit to the players of the game.

25 2. A pack of cards for playing base ball, having the individual cards provided with matter corresponding with the several plays incident to the standard game of base ball, and having certain cards provided, in addition to the indicating matter, with numerals from one to nine, whereby proper credit of 30 35 a play may be given to the individual player.

3. A pack of cards for playing base ball, each of the cards being provided with matter corresponding to a play, certain cards bearing in addition to the indicating matter, 40 numbers from one to nine to enable credit being given to the card representing the player making the same, and certain other cards bearing two sets of numbers, whereby proper credit may be given to the parties 45 playing the game.

4. A pack of cards consisting of a single deck for playing base ball divided into a series of sets, the cards of certain of the sets indicating plays by the batter resulting in 50 an "out" for his team, each of said cards being marked to indicate the player or players of the opposing team making the particular play indicated on the card with the result of an "out" for the batter.

5. A pack of cards consisting of a single deck for playing base ball divided into a series of sets, the cards of certain of the sets indicating plays by the batter resulting in an "out" for his team, each of said cards being marked to indicate the player or players of the opposing team making the particular play indicated on the card with the result of an "out" for the batter, other 60 series of sets indicating "safe" plays by 65 the batter.

In testimony whereof I affix my signature in presence of two witnesses.
